UNITED STATES PATENT OFFICE.

ALFRED FISHER, OF CHICAGO, ILLINOIS.

METAL FURNACE.

No. 828,881.

Specification of Letters Patent.

Patented Aug. 21, 1906.

Application filed July 14, 1905. Serial No. 269,580.

To all whom it may concern:

Be it known that I, ALFRED FISHER, a citizen of the United States, and a resident of Chicago, in the county of Cook and State of Illinois, have invented certain new and useful Improvements in Metal Furnaces; and I do hereby declare that the following is a clear and exact description of the same, reference being had to the accompanying drawings, and to the letters of reference marked thereon, which form a part of this specification.

This invention relates to improvements in furnaces, and more particularly to a crucible-furnace.

Heretofore of the brass and any other metal furnaces of the class in which crucibles are used the air-blast has usually been directed against the crucible, with the effect of quickly wearing or eroding the same away, soon reducing the strength of the crucible sufficiently to endanger the loss of the charge by breakage. Furthermore, in such furnaces heretofore the heat has been usually applied unequally to different parts of the crucible, with the effect of heating the charge unevenly and not only endangering the furnace and crucible, but burning a part of the metal before the remainder has been thoroughly melted. Sometimes also in devices of the class the furnace has been so constructed that the breakage of the crucible within the furnace acts to clog the furnace, and should the metal harden therein it is practically impossible to remove the same from the furnace without injury to the furnace.

The object of this invention is to provide a construction in which all parts of the crucible must receive the same heating effect, insuring uniform temperature in all parts of the crucible, thereby melting the metal evenly, insuring a uniform reduction of the charge, and in which the blast and heat of the furnace flow centrifugally around the crucible, affording maximum heating effect but minimum wearing or eroding effect upon the crucible.

A further object of the invention is to provide a nozzle in connection with the furnace-blast burners whereby the fuel-supply and the blast can be accurately regulated to the work required, enabling the operator to secure a range of temperature usually impossible heretofore and also enabling the operation of the furnace to be perfectly controlled and enabling the furnace to be used continuously, enabling many charges to be taken

therefrom as compared with the furnaces heretofore in use.

The invention consists in the matters hereinafter described, and more fully pointed out and defined in the appended claims.

In the drawings, Figure 1 is a front elevation, partly broken, of a furnace embodying my invention. Fig. 2 is a rear elevation of the same. Fig. 3 is a central vertical section of the same. Fig. 4 is a top plan view thereof, partly in section. Fig. 5 is a central horizontal section of a furnace embodying my invention and provided with two burners. Fig. 6 is an enlarged horizontal section of a burner embodied in my invention. Fig. 7 is a side elevation of the same. Fig. 8 is a section taken on line 8 8 of Fig. 6.

As shown in the drawings, said furnace embraces a bottom layer of fire-clay, fire-brick, or other suitable refractory material (indicated by A) and supported, as shown, on a circular plate a, preferably of metal. Connected with said bottom plate by bolting or riveting is a side plate a', which extends upwardly above the base layer A and affords a part of the retaining-casing for the wall of fire-bricks a², which on the outer side tapers conically upward and on the inner side converges upwardly, providing a circular pot or furnace, which at the bottom curves inwardly, affording a conical chamber. Inclosing said fire-brick a² is an outer jacket or lining a³ of sheet metal, rigidly bolted or otherwise secured to the upper edge to the jacket or liner a', and supported on the top of said fire-brick a² are fire-brick a⁴, the outer sides of which extend vertically and the inner sides of which are shaped to afford when built into the furnace a cylindric chamber of practically uniform diameter. Extending to the top of the fire-pot and inclosing said upper layer of fire-brick is a jacket or liner a⁵ of metal, rigidly secured on the upper edge of the jacket-sheet a³. On the top of said sheet or plate a⁵ and secured thereto by means of an angle-iron connecting-band a¹⁰ is a top plate a⁶, rigidly bolted thereto and having a central aperture above the furnace of greater diameter than the interior diameter of the furnace.

Extending outwardly and downwardly through the front of the furnace and the jacket-wall a', at the bottom thereof, is a passage a⁷, at the outer end of which is a clay-lined spout a⁸, and on the opposite side of the furnace and opening through the wall thereof through one or more of the fire-bricks a⁴ is a

stack a^9 , constructed of sheet metal and lined with fire-bricks or other refractory material.

Hinged on the rear side of the furnace upon lugs b , rigidly bolted to the rear wall of the furnace, is a lid comprising a circularly-bent cast-metal outer casing B , affording an upwardly-extending wall having an inwardly-directed lower flange affording an aperture therethrough coincident with the aperture in the plate a^8 and in which is supported a fire-clay or fire-brick filler b' , provided with a central upwardly-enlarging aperture therethrough having at its bottom approximately the diameter of the crucible to be contained in the furnace. A cover-plate b^2 is rigidly bolted or otherwise secured and provided with a central aperture therethrough of greater diameter than the aperture through the fire-clay contained in the lid. As shown, rigid arms b^3 extend rearwardly from said lid and are provided at their outer ends with counterweights b^4 and, as shown, are apertured intermediate the ends to receive a pintle-rod b^5 , which passes through the ends of the brackets or arms b and through said arms and affords the hinge for said lid. As shown, also, a removable cover is provided to close the central aperture through the hinged lid and comprises a cast or sheet metal casing b^6 , having secured at the top thereof apertured lugs or handles b^7 and at its bottom provided with an inwardly-turned flange or lip, as shown in Fig. 3, and in which is secured a fire-clay or fire-brick or any suitable refractory lining. A vent-aperture is also provided through the top of said removable cover to provide for the escape of a part of the fumes or gases. The front side of the lid is adapted to be locked to the front casing or wall of the furnace. A forwardly-directed bracket C is provided at its end with a lever c , journaled transversely therein and having a cam c' thereon adapted to engage a hook c^2 , pivotally engaged on the front wall or casing of the furnace, so that when said lid is closed and the hook or latch c^2 swung over said cam operation of the lever acts to positively secure the lid in place.

Within the furnace is seated an upwardly-tapering central conical block or pedestal D , having a flat top and having its sides curved inwardly to correspond with the side walls. Upon this pedestal is supported a crucible D' . Said block or pedestal is of course constructed of fire-clay or other refractory material and is of a height to elevate the top of the crucible to near the top of the furnace, as shown in Fig. 3.

One or more blast-burners are provided adapted for the use of crude oil or any suitable hydrocarbon, and, as shown, each comprises a conical twyer affording a restricted nozzle and constructed of cast metal or any suitable material and which is shown as secured in the outer casing or wall of the fur-

nace and directed inwardly and obliquely downwardly and approximately tangentially with the inner wall of the furnace, as shown in Figs. 1, 4, and 5. Within the twyer E , as shown, is provided a hydrocarbon-pipe e , the inner end of which extends approximately to the restriction in the twyer and the outer end of which is connected in and communicates through the outer end of the twyer, by means of a needle-valve e' , with a crude-oil or other hydrocarbon pipe e^2 .

Secured beneath and opening into the twyer is an air-regulating valve E' , which is shown as a plug-valve, the closure e^3 of which is tubular and has a side port through which it opens into the twyer, as shown in Figs. 6 and 8. Connected in the end of said valve and delivering through the plug e^3 into the twyer is an air-blast pipe E^2 , which is connected with a blower of any suitable kind, adapted to produce the desired blast-pressure within the furnace. Connected in the side of said valve E' is an air-relief pipe E^3 , the outlet to which is also controlled by the plug-closure e^4 and which opens to the atmosphere. The arrangement of said valve is such that when the plug is adjusted to admit the blast to the twyer the relief-pipe E^3 is closed thereby, and when the closure is rotated to exclude blast from the twyer or partly exclude the same the blast, or a portion thereof, is delivered through the relief-pipe. This enables the force of the blast to be regulated to suit the requirements of use.

The furnace may be constructed in any suitable manner to support the blast-burners in the position described. Conveniently and preferably, however, the fire-brick which form the first course above the bottom of the furnace and those in the base are shaped as shown in Fig. 5 to afford an approximately rectangular corner for the furnace at the side or sides through which the burner or burners enter, thus facilitating laying up the furnace, insuring the proper angle of the burner with the inner wall, and also simplifying the repairs.

One or more burners may be employed, as preferred. As shown in Fig. 5, two burners are employed on diametrically opposite sides of the furnace and which are arranged to send the blast in the same direction around the crucible. In this construction the air-pipes, the hydrocarbon-pipes, and the relief-pipes are connected in both tuyers, thus enabling uniformity of action to be secured without difficulty.

The operation is as follows: With the furnace constructed as described the metals to be treated are placed within the crucible, if preferred, through the lid. The furnace is then closed, the burners lighted, and the valve E' actuated by means of a lever e^5 to admit the required blast into the furnace, said blast being of course proportionate to

the amount of hydrocarbon used and the temperature to be attained, both of which can be regulated by adjustment of the needle-valve by means of the hand-wheel e^a and the adjustment of the valve E' by means of the lever e^b . Inasmuch as the blast is directed obliquely and downwardly against the inner wall of the furnace, a centrifugal blast is sent around the crucible, exerting a maximum heating effect, but having no erosive effect thereon. A portion of the gases and fumes escape through the cover; but the greater part thereof escapes through the stack a^a , which of course may be provided with any desired damper for regulating and controlling the draft in the same. Owing to the peripheral deflection of the current or currents from the blast the metal within the crucible is quickly and uniformly reduced. The hook c^a is then released, and the lid is swung up by its counterweight, permitting the removal of the crucible for pouring, as usual. During the period following the reduction of the metal and including the period of pouring and the return of the crucible to the furnace and charging the same the air-blast is deflected from the twyers by rotating the valve-plug to direct the blast through the relief pipe or pipes or sufficient thereof to prevent great loss of heat within the furnace while pouring. The crucible can be immediately returned to the furnace again charged, either before closing the lid or through the lid D' , which is so constructed that should the metal not fill readily into the crucible a part of the same may extend upwardly within the lid. The blast is then again turned on by means of the needle-valve and the lever e^b , and the operation immediately recommences, thus enabling the burners to be continuously used without inconvenience. Should a plurality of furnaces be connected with the same blast-pipe E^a , the relief-pipes afford means for cutting out the blast from any one of the furnaces without effecting the blast of the others, and, furthermore, should two or more burners be used in a single furnace all the burners for a furnace may be connected in the same blast-pipe and with the same relief-pipes, thus insuring uniformity for both burners. Should a crucible break, the passage in the bottom of the furnace, which is ordinarily stopped with clay, is picked open, permitting the molten metal to run from the furnace without injury either to the furnace or metal.

Owing to simple construction of the furnace and the fact that the individual blocks or bricks of fire-clay or other refractory material are molded to lay readily to the construction, affording ample support for the burners, it is evident that the construction is exceedingly cheap, affords extreme simplicity, great durability, and economy of operation and maintenance. Furthermore, it is

evident that many details of arrangement and construction may be varied. I therefore do not purpose limiting this application for patent otherwise than necessitated in the prior art.

70

I claim as my invention—

1. A furnace of the class described having a fire-pot provided with a rounded bottom having a greater interior diameter than the top and a peripherally and downwardly directed blast-burner, opening obliquely through the side of the furnace and adapted to direct a reducing-blast centrifugally around the furnace-crucible.

2. In a furnace of the class described, a crucible therein, blast-burners directed downwardly and inwardly of the furnace approximately tangent to its inner periphery and a concave bottom in said furnace adapted to direct the blast from the burners in an upwardly-directed spiral about the crucible.

3. In a furnace of the class described a crucible, a support therefor affording with the furnace-bottom a rounded deflecting-surface, one or more burners arranged to direct its blast obliquely against the inner periphery of the furnace and downwardly against said deflecting-surface and means for regulating the blast of said burners.

4. In a melting-furnace the combination with a furnace constructed of molded refractory material, of an outer metallic casing fitted thereto, a stack leading from the furnace, one or more blast-burners opening obliquely and downwardly through the side wall of the furnace and directing the blast therefrom away from but centrifugally around the crucible, means for deflecting said blast from the bottom of the furnace spirally upward and a regulating-valve for the blast acting to direct the same into or out of the furnace.

5. In a metal-melting furnace the combination with a crucible-support of upwardly-converging, encircling side walls surrounding the crucible and affording with the support a rounded bottom adapted to direct the blast in an upwardly-directed spiral and one or more hydrocarbon blast-burners opening obliquely inwardly and downwardly toward said bottom, said side walls affording an increased thickness at the point of insertion of the burner.

6. In a melting-furnace, a fire-pot having an enlarged bottom, a crucible-support therein affording with the bottom a rounded deflecting-surface, a crucible thereon and one or more blast-burners extending through the walls of the furnace and adapted to direct a blast against said deflecting-surface and in an upwardly-directed spiral about the crucible.

7. In a melting-furnace the combination with the side walls thereof of one or more blast-burners opening therethrough near the bottom and directed both tangentially and

125

130

downwardly, a crucible and a support therefor affording with the walls of the furnace a rounded deflecting-surface adapted to direct the blast centrifugally and upwardly about the crucible.

- 5 8. In a melting-furnace the combination with a fire-pot of a crucible therein, a lid hinged on the furnace and provided with an inverted conical aperture therethrough, registering with the top of said crucible, a cover adapted to close said aperture and provided with a central vent therein, a hook pivoted

on the furnace, a cam-lever carried on the lid adapted to be engaged thereby and hold the lid in closed position and counterweights for said lid.

In testimony whereof I have hereunto subscribed my name in the presence of two subscribing witnesses.

ALFRED FISHER.
